[57] CLAIM

The ornamental design for a medical container for injectable substances, substantially as shown and described.

DESCRIPTION

FIG. 1 is an elevational view of a medical container for injectable substances showing my new design;

FIG. 2 is an elevational view looking from the right of FIG. 1;

FIG. 3 is an elevational view looking from the left of FIG. 1;

FIG. 4 is a top plan view;

FIG. 5 is a bottom plan view; and

FIG. 6 is an elevational view of an alternative design similar to that shown in FIG. 1.

*FIG. 1.**FIG. 2.*Fig. 3.

Fig. 4.

Fig. 5.

Fig. 6.
